US0D1095312S

(12) **United States Design Patent** (10) Patent No.: **US D1,095,312 S**
(45) Date of Patent: ** Sep. 30, 2025

(54) **GEM**

(71) Applicant: **Koninklijke Asscher Diamant Maatschappij B.V**, Amsterdam (NL)
(72) Inventors: **Mike Edward Asscher**, Amsterdam (NL); **Lita Natascha Asscher**, Amsterdam (NL)

(73) Assignee: **Koninklijke Asscher Diamant Maatschappij B.V.**

(**) Term: **15 Years**

(21) Appl. No.: **29/991,860**

(22) Filed: **Mar. 4, 2025**

(51) LOC (15) Cl. **11-01**

(52) U.S. Cl. **D11/89**
USPC **D11/1-2, 26-29, 89-92, 157, 172;**
D26/154

(58) **Field of Classification Search**
USPC D11/1-2, 26-29, 89-92, 157, 172;
D26/154
CPC A44C 17/00; A44C 17/001; A44C 17/007;
A44C 17/008
